UNITED STATES PATENT OFFICE.

DANIEL E. WOODHULL, OF NEW YORK, N. Y., ASSIGNOR TO AMERICAN BANK NOTE COMPANY, A CORPORATION OF NEW YORK.

BOOKBINDING-MACHINE.

1,037,097.

Specification of Letters Patent. Patented Aug. 27, 1912.

Application filed December 15, 1908. Serial No. 487,623.

To all whom it may concern:

Be it known that I, DANIEL E. WOODHULL, a citizen of the United States, residing in the borough of Manhattan, city, county, and State of New York, have invented certain new and useful Improvements in Bookbinding-Machines, of which the following is a specification, reference being had therein to the accompanying drawings, which form a part thereof.

My invention relates to book binding machines, and more particularly to a type thereof adapted to fold a reinforcing strip of tape, cloth or paper, if desired, upon a pamphlet.

The machine of my invention has application more particularly to the binding of coupon bonds and other similar pamphlets, wherein the binding is for the purpose mainly, of giving a neat finish to the bond rather than to act as a hinge. This binding is for both sides of one edge of the bond, and customarily, the various sheets constituting the bond are previously united by staples. Heretofore the binding or backing strips have been applied by hand, and this work required a high degree of skill to avoid the soiling or mutilation of the bonds, which condition has made the operation of binding fairly expensive. To fully appreciate the necessity for this high grade of work, it must be understood that the bonds, for the binding of which this machine is intended, reach the binding department in numbered sets so that the destruction of one of the articles causes considerable additional inconvenience, labor and expense and frequently results in great confusion.

The main object of my invention is to apply a backing or binding strip to a coupon bond by mechanical means which will fold a strip of material across the hinge or back of the bond and upon both sides thereof, thus supplanting the old hand methods, and not only insuring increased capacity, but uniformity and precision in the work itself.

A further object is to provide a machine of this character embodying a strip feeding and folding mechanism, a glue pot, for making the same adhesive, a bond feeding mechanism, and a presser mechanism for applying the adhesive strip to the bond after it has been folded thereon by the feeding and folding mechanism.

A still further object is to provide a ma-

chine of this character which will apply a continuous strip of cloth or paper to bonds in rapid succession, and thus permit a high efficiency in the machine, while running at a comparatively low rate of speed.

A still further object is to provide a machine adapted to apply a continuous strip to successive bonds, wherein the bonds will be so spaced apart, as to afford ample room for the separation and trimming thereof without likelihood of mutilation.

A still further object is to provide a machine of this character wherein a continuous strip is applied to a succession of bonds and said strip is automatically severed into lengths approximating the length of the binding, after being attached to the bonds.

A still further object is to provide a machine of this character, in conjunction with a strip feeding and pasting mechanism, means whereby a continuous strip will be scored while passing through the machine, so as to facilitate the folding operation and insure precision in such operation.

A still further object is to provide in a machine of this character, a synchronized intermittent movement of the strip feeding and folding mechanism, the pamphlet feeding mechanism, and the shears, whereby the application of the binder will be by a continuous operation, and the succession of bonds, enchain'd by the binder strip, may be separated one at a time and discharged separately into the collecting mechanism of the machine.

A still further object is to provide a feeding mechanism which will feed the coupon bonds, in a perfectly flat position so as to prevent the displacement of the sheets, or the creasing or wrinkling thereof.

A still further object is to simplify the structure of the machine by utilizing a feeding roll for pressing the strip upon the bond, and feeding the strip forward to position it properly for the next bond.

A still further object is to provide a folding mechanism wherein the strip will be gradually folded so as to pass over both sides of the bond at the hinge thereof, with the adhesive surfaces presented inwardly, and the said surfaces held separated so as to prevent their adhering together before the bond has been inserted therebetween.

A still further object is to provide various adjustments for the feeding mechanism,

and the shears, whereby bonds of different widths may be bound in a machine.

A still further object is to provide a suitable adjustment for the presser roll to permit its regulation to insure the proper application of the strip to the bond. And a still further object is to provide a machine of this character which will be simple in design, and in its mode of operation, and inexpensive to produce.

The invention consists in the novel features of construction and combination of parts hereinafter set forth and described, and more particularly pointed out in the claims hereto appended.

Referring to the drawings:—Figure 1 is a plan view of a machine embodying my invention, having three bonds thereon shown partly in full lines and partly in dotted lines, the feeding shelf and the collecting shelf being partly broken away; Fig. 2 is a side elevation of the machine shown in Fig. 1; Fig. 3 is a detail view, in perspective, of the strip folder; Fig. 4 is a detail perspective view of a portion of the shear-actuating mechanism; Fig. 5 is a detail view of a portion of the feeding chain showing an adjustable clip thereon; Fig. 6 is a detail view in side elevation of one pair of feeding rolls and the presser rolls; Fig. 7 is a detail view of the mechanism intermittently actuating the bond feeding chains and the shears, and Fig. 8 is a detail view of the strip creasing or scoring and tensioning mechanism.

Like letters refer to like parts throughout the several views.

In the embodiment of my invention, shown in the drawings, the frame A of the machine is shown as supporting a sectional table consisting of three parts, B, B', B'', so spaced apart as to leave ways or channels C, C', between said sections for the carrying chains of the feeding mechanism. At one end of the sectional table is a feeding shelf D, having a bevel leading to the machine top, and at the other end thereof, is a collecting shelf E, having a retaining flange E'. Alined with the part B'' is a guide flange F, which serves as a guide for the bonds as they pass through the machine.

The main driving mechanism consists of a pulley G driven from a motor H or any other desired source of power.

In the further description of the machine, for the purpose of greater perspicuity, the various mechanisms will be considered separately, and described with relation to the succeeding operations on any bond, although all of these operations are carried on simultaneously, each performing its function, at the same time, but upon a different object, or a different part of one object. A logical division of the machine along these lines would therefore consist of the bond feeding mechanism; the strip pasting and guiding

mechanism; the strip folding mechanism; the strip presser mechanism, which would include the mechanism employed for holding the bond in the proper position while the binding is being applied thereto; and the shear mechanism, the feeding and collecting shelves, requiring no detailed description beyond that above given. Before entering into this detailed description, it is necessary to point out that through the necessity for synchronizing the actuation of the various mechanisms, it is desirable to have them all actuated from the same main shaft, and to secure that slight interval of rest necessary or desirable to permit the separation of each bond after it has been bound, and to have all of these movements intermittent. With this aim in view, I provide a ratchet wheel a carrying a gear a', and a lever a'', carrying a pawl a'', oscillating about the axis of said ratchet a. The pawl a'' is necessarily spring-pressed. Geared to the pulley G, by the entrained gears G' is a gear wheel G'' and pivotally connected eccentrically of the gear G'' and adjustably to the end of the lever a'', is a connecting rod b. This mechanism being common to all of the mechanisms described is referred to at this point.

Mounted at opposite ends of the machine and below the top thereof are parallel shafts c c' carrying sprocket wheels c² c³ about which run sprocket chains c⁴, the diameter of the sprockets being such as to bring said chains below the top level of the machine top. The sprockets c² c³ are so spaced apart as to cause said chains to run in the channels C C' provided in the top for this purpose. The chains, as shown clearly in Fig. 1, pass under the feeding shelf D so that a bond fed from said shelf will be delivered upon the machine top above said chains. These chains being positioned below the surface of the machine top, the actual feeding movement is accomplished by means of projections spaced apart upon the said chains, a distance sufficient to accommodate the bonds between the succeeding projections, which projections extend above the said top surfaces. Preferably these clips are made of spring metal, as shown in Fig. 5, and are adapted to be sprung over and engage a pivot in the chain links. The clips on the opposite chains c⁴ c⁴, it is needless to say, must be placed directly opposite each other, so as to afford contacting surfaces on the same straight line at right angles to the direction of movement of the chains, and thus insure a parallel feeding movement of the bonds. In order to insure high capacity, the succeeding clips should be arranged as near together as possible, leaving sufficient clearance between the succeeding bonds, to permit a field for the actuation of the shears. It is desirable to provide such an adjustment

of the distance between the clips as will accommodate the machine to slight variances in the widths of different bonds, such as would not materially affect the predetermined feeding movements of the pawl and ratchet mechanism. This adjustment would, however, permit the variation of this feeding movement by the adjustment of the connecting rod *b* in a manner to be hereinafter described. To accomplish this result, the clip *d* is provided with one vertical edge *d'*, and a stepped edge *d²*, which step would bring the contacting point substantially midway between the pivots of any link. It will thus be observed that the distance between two clips may be shortened by simply turning the clip around, or it may be lengthened to an extent equaling the length of a link by attaching the clip to the succeeding pivot pin, or of a half of a link by attaching it to said pin and turning it with the straight edge *d'* presented in the direction of the feeding movement.

If the adjustment is sufficiently great to necessitate a variance in the feed, such may be accomplished by releasing the end of the connecting rod *b* on the oscillating lever *a²* and raising it to a point nearer to, or farther away from, the axis of oscillation of said lever.

In mesh with the gear *a'* is a pinion *e* carrying a gear *e'* and a sprocket *e²*. Extending from the sprocket *e²* about a sprocket *e³* carried by the shaft *c'* is a sprocket chain *e⁴* by means of which the chains *c⁴* receive a unidirectional, intermittent or step-by-step feeding movement.

Mounted on the frame of the machine, is a reel *I* adapted to carry a roll *J* of strip binding cloth or paper; and disposed between said reel and the folder mechanism is a mechanism *K* for creasing and tensioning the strip, and a glue pot *L* for applying glue thereto. The said glue pot has mounted therein a pasting roller *f* having mounted on opposite sides thereof in the direction of traverse of the strip, guiding and tensioning rollers *f', f²*. The glue pot is heated in any desired manner as by the burner *L'*. The tensioning and creasing mechanism *K* comprises a metallic roller *g* having a central rib *g'* thereon adapted to fit into the circumferential recess in the roller *g²*, the roller *g* being flanged to guide the strip in passing through this mechanism. Disposed between the roller *g* and the reel, is a flanged guiding and tensioning roller *g³*. The roller *g²* is mounted in movable bearings *g⁴* and a suitable adjustment screw *g⁵* is provided for the purpose of regulating the pressure exerted upon the cloth or paper binder strip while passing through this mechanism. The entire creasing mechanism is positioned between the glue pot and the reel and serves as a tensioning device to prevent the overrun-

ning of the reel as well as to avoid the presence of slack between the glue pot and the folder mechanism. To minimize likelihood of the lapping of the strip between the guide and tension roller *g³* and the creasing rollers *g, g²*, I provide a cover *g⁶*, for said rollers which holds the strip flat while it is passing through this mechanism. After the strip leaves the glue pot, with the glued surface presented downwardly, for the twofold purpose of preventing dust and dirt settling thereon and the contact of the adhesive surface with the machine parts, it extends parallel with the chain *c⁴* and passes around the guide roller *h*, and thence laterally away from said chains to a guide roller *h'*, the axis of which is so pitched as to direct the strip toward the folder mechanism and permit it to be turned or twisted in the manner shown in Figs. 1 and 2 of the drawings. The rollers *h, h'* are idlers, and act merely as guides for the strip. The guide flange *F* has an opening therein through which the strip *J* passes to the folder mechanism which will now be described.

The folder which is shown in detail, in Fig. 3, comprises a plate *i* having side flanges *i', i²*, which at their forward ends (with reference to the initiation of the folding movements) are spaced apart the width of the strip and gradually converge toward their other end, so as to gradually fold the sides of the strip toward each other. One side of the folder is open to permit the bond to pass between said flanges and be inserted between the folded sides of the strip. Under some conditions, the bond might spring upwardly and engage the top fold of the strip prematurely, or said strip might collapse and thus be improperly applied to the bend, and, while the folder heretofore described will operate successfully, I prefer to provide a separator *j* attached to the upper flange *i* by means of the clip *j'* which acts as an upper guide surface for the bond passing through the folder and at the same time prevents the top fold of the web from engaging same, until it has been properly folded over by the converging flanges *i', i²* toward the discharge end thereof. The use of the clip *j'* permits the separator *j* to be detached from the machine when the conditions are such as not to require it to insure correct work.

The presser mechanism consists of two members, one for applying the strip to the bond, after it has been positioned, or laid, by the folder, and the other for pressing the various leaves of the bond together and holding them against lateral displacement, while the binding strip is being placed thereon or pressed to place. The first of these members above referred to consists of a roller *k* having an elastic surface, as soft rubber, mounted above an idler *k'*, also having a

soft rubber surface, mounted on the frame of the machine. These rollers k k' are opposite the folder i so that as the bond or other pamphlet passes from said folder with the binding strip laid thereon, the bound end of the bond will pass between said rollers and be pressed firmly therebetween. The roller k is mounted on a shaft carried in an adjustable housing k^2 , which shaft is rotated by means of a gear k^3 in mesh with the gear e' . The adjustment screws k^4 are for the purpose of regulating the pressure exerted by the roller k . This construction with proper regard for the diameter of the roller k gives a peripheral travel to said roller equaling the lineal traverse of the feeding mechanism and thus prevents the buckling or wrinkling of the bonds by reason of any checking of the feeding movement at this point. While primarily, a power driven rotary presser is for this purpose, it has the secondary feature of insuring a uniform feed of the bound end of a bond.

Mounted above the machine top is a shaft l passing over the folder plate i intermediate its ends, which shaft has a gear l' of the same diameter as, and entrained with, the gear k^3 by the idler gear l^2 . Mounted on the shaft l at widely divergent points, so as to exert such a pressure on the bonds along the same straight line, as to prevent any twisting thereof during the application of the binding strip thereto and the subsequent operation of the presser mechanism thereon, are rollers m of elastic material or provided with an elastic cover, and of the same diameter as the presser roller k . Mounted in the top part of B' and B^2 respectively, beneath these rollers m , are anti-friction rollers m' between which and the rollers m the bonds are gripped. The shaft l is driven at the same speed as the shaft carrying the roller k , and consequently the rollers k m are all driven at the same speed and have a peripheral travel equaling the traverse of the chains c^4 , thus avoiding any turning of the bonds through diversity of the feeding movement between the rollers k m and the said chains c^4 . It will be observed by reference to Fig. 1, that one of the rollers m engages the bonds at a point near the folder i and that the other roller m is so positioned as to engage any size of bond being fed by the chains c^4 .

Adjustably mounted on the top B^2 is a frame n carrying a fixed shear blade n' upon the plane of the machine top and a removable blade n^2 positioned upon an arm n^3 . The guide flange F does not extend beyond the folder i , thus leaving clearance for the presser mechanism and the shear mechanism heretofore described.

Mounted beneath the machine top is an oscillating shaft o having slidably and adjustably mounted thereon, an arm o' con-

nected by a link o^2 with an arm n^3 , the shears being actuated through these members. Adjacent to the other end of the shaft o is an arm o^3 pivotally connected to a slide p mounted on the frame of the machine which slide has vertical movement and is adapted to oscillate said shaft o . The slide p is slotted at p' as indicated in dotted lines in Fig. 7 and straddles the shaft of the gear G^2 . Adjacent to the bottom of the slide p is an anti-friction roller p^2 which roller is adapted to be engaged by a cam q carried on the shaft of the said gear G^2 . Acting on the shaft o is a spring r tending to normally open the shears, the cam q tensioning the said spring when the shears are actuated. It will be observed by reference to Fig. 7, that the cam q is so set as to actuate the shears while the pawl a^3 is being reset preparatory to the next feeding movement of the various elements of the binder, thus causing the shears to separate the succeeding bonds by severing the continuous strip between same, during this interval of rest.

It will be observed that the various mechanisms all being actuated through the rotation of the gear G^2 their movement will be accurately timed, and the likelihood of damage or a disarrangement of parts will be reduced to a minimum.

I have indicated the bonds passing through the machine by the letter M , the various leaves thereof being secured near one end by staples, or other securing means.

The operation of the herein described machine is substantially as follows:—The bonds M are stacked upon the feeding shelf D and fed therefrom to the machine top B , B' , and B^2 with the bound edge against the guide flange F . As fed, the bonds are positioned between succeeding clips d and as the machine is intermittently operated, the bond may be properly positioned during the interval of rest, which, however, is slight. Assuming that any bond is being fed through the machine, the operation would continue as follows:—The gear G^2 having passed the center, oscillates the lever a^2 through the connecting rod b and with the pawl a^3 would turn the ratchet a and the gear a' carried on its shaft so as to impart a simultaneous forward feeding movement to the sprocket chains c^4 through the pinion e , the sprocket e^2 , the sprocket chain e^4 , the shafts c c' and the sprocket wheels c^2 c^3 . As the said chains advance, the clips d thereon engage the bond adjacent to opposite edges thereof and slide said bond along the machine top toward the folder mechanism. Before starting the machine, the strip is drawn from the roll J on the reel I , threaded through the creasing and tensioning mechanism K ; under the roller f' ; over the gluing roller f ; under the roller f^2 ; through the folder i and under the feeding

and presser roller k . Hence, as the machine operates, the binding strip is fed forward at the same speed as the bond itself, the gearing actuating the roller k as heretofore described, imparting to said roller a peripheral travel equaling said feeding movement of said chains c^4 , c^4 . While the binding strip, in passing through the glue pot and up to the roller k , is extended on a plane parallel to the top of the machine, it is turned after it leaves the roller k' and passes to the folder i at right angles to the said top. As it passes through said folder the opposite edges thereof are gradually turned toward each other, the crease centrally of said strip insuring the fold coming centrally of said strip. The crease is shown clearly in Fig. 3, as well as the folding action of the part i . The converged flanges i' , i^2 gradually bring the turned sides of the strip closer together so that at the point where the strip leaves said folder, they are so close together as to actually engage the bond. To insure the accurate positioning of the strip upon the bond, the operation of the feeding chains s^4 and the mechanism for applying the adhesive to, and advancing the strip are so synchronized as to have each bond M enter the folding mechanism and travel therethrough simultaneously with that portion of the strip which is to form the binder therefor, so that the strip is folded directly upon the bond, thus greatly simplifying its application thereto. When the separating strip j is used, however, only the bottom of the bond will engage with the strip, this portion of the strip being supported upon the flange i^2 and being applied to the bond perfectly flat. The upper folded portion of the strip is prevented from engaging the bond till it has left the folder i thus preventing the strip, under any circumstances, (as through softness in the material of the strip) being applied to the bond except when folded over to the full extent so as to lie perfectly flat without wrinkles. The separator j would also have the effect of defining a straight line along which the strip will be folded. As each bond enters the folder i between the flanges i' and i^2 thereof, it will pass between the rollers m and their opposed rollers m' which not only has the effect of feeding them forwardly at the same speed as the movement of the chains c^4 , but will keep them perfectly straight and hold them against any tendency to turn by reason of the resistance due to the engagement thereof with the gummed surface of the strip. This engagement continues until the strip has been applied to substantially the entire edge of the bond and will cease only at a point when likelihood of the improper application of the binder to the bond has ceased. As the forward edge of each bond leaves the folder i it passes between the presser rollers

k , k' which apply the laid strip. The rollers k , m being of the same diameter, and running at the same speed, any such displacement of the bond, or any leaf thereof, as would tend to produce an improperly bound bond is avoided. The bonds in passing through the machine, being spaced slightly apart by the clips d , the section of the strip between the bonds will be folded upon itself and pressed firmly together by the rollers k , k' . The eccentric connection of the connecting rod b with the shaft G^2 will be on center, when the bonds are so positioned that the space between them is between the shears n' and n^2 and the various bonds will therefore come to rest while all of the rollers k , m are still in engagement with the bond being bound. When all of the mechanisms are thus at rest, the cam q will force the slide p downwardly, turning the shaft o , and, through the arms o^3 and o' , actuating the connecting link o^2 and the arm n^3 , thus operating the shears to sever the folded strip between any two adjacent bonds. This manner of severing leaves a short tab extending beyond the bond as shown clearly in Fig. 1. This tab is left in order to avoid the necessity for setting the machine so close as to incur a possibility of the mutilation of the bond by said shears. These tabs may be afterward severed by hand. The shears having been actuated will be opened again by the spring r and the feeding movement of the strip, chains and rollers will be resumed for the next bond. After each bond has been separated from the others, in this manner, it is fed by the clips d and chains c^4 to the end of the machine top, and thence discharged upon the collecting shelf E . In Fig. 1, I have shown a bond upon said shelf.

The operation of the creasing and glue applying mechanism needs no detailed description, such being apparent from the drawings and foregoing description of each.

By an intermittent feeding mechanism for the bonds, and intermittently actuated shears, operated when the feeding movement is at rest, I am enabled to run the machine at a high rate of speed, while the binding strip is being applied to the bond, and yet afford an ample interval of rest for the actuation of the shears without likelihood of mutilating the bonds thereby. This interval of rest also facilitates the feeding of the bonds, as precision is necessary, and cannot be secured when the machine is running continuously at a high rate of speed, with the agencies employed.

It is not my intention to limit the invention to the precise details of construction shown in the drawings, as such may be varied without departing from the spirit and scope of the invention.

Having described my invention, what I

claim as new, and desire to have protected by Letters Patent, is:—

1. In a book binding machine the combination with means making a strip adhesive, a folding mechanism whereby the strip is laid over the edge of a bond, a presser mechanism whereby the said web is applied to a bond, and shears whereby said strip is severed into short lengths after it is applied to a bond, of a feeding table having a plurality of parallel channels therein, a plurality of endless carrying members mounted in said channels, projections carried by said members extending above said table, the projections on the different members being opposite each other, a feeding shelf, and a collecting shelf, at opposite ends of said table, a driving mechanism imparting a uni-directional intermittent movement to said carrying members, and means respectively actuating said presser mechanism simultaneously with said carrying members, and said shears during the interval of rest of said members.
2. In a book binding machine, the combination with means making a strip adhesive, a folding mechanism whereby the strip is laid over the edge of a bond, a presser mechanism whereby the laid strip is applied to a bond, and shears whereby said strip is severed into short lengths after it is applied to a bond, of a feeding table having a plurality of parallel channels therein, a plurality of endless carrying members mounted in said channels, projections adjustably mounted on each of said members, and spaced apart thereon to accommodate a bond therebetween, said projections extending above the table, and those on one member being opposite those on the other, a feeding shelf, and a collecting shelf at opposite ends of said table, a driving mechanism, imparting a uni-directional intermittent movement to said carrying members, and means respectively actuating said presser mechanism simultaneously with said carrying members and said shears during the interval of rest of said members.
3. In a book binding machine, the combination with means making a strip adhesive, a folding mechanism whereby the strip is laid over the edge of a bond, a presser mechanism whereby the laid strip is applied to a bond, and shears whereby said strip is severed into short lengths after it is applied to a bond, of a feeding table having a plurality of parallel channels therein, sprocket wheels mounted at each end of each said channel, sprocket chains extending about said wheels, and seated in said channels, a plurality of spring clips mounted on each said chain, said clips being spaced apart on each chain to accommodate a bond therebetween, and those on one chain being opposite those on the others, each said
- clip projecting above said table, and having one straight edge, and one edge stepped, whereby the distance between succeeding clips may be varied by adjusting the same on the chain, a feeding shelf, and a collecting shelf, at opposite ends of said table, a driving mechanism, imparting a uni-directional intermittent movement to said carrying members, and means respectively actuating said presser mechanism simultaneously with said carrying members and said shears during the interval of rest of said members.
4. In a book binding machine, the combination with means making a strip adhesive, a folding mechanism whereby a strip is laid over the edge of a bond, a presser mechanism whereby the laid strip is applied to a bond, and shears whereby said strip is severed into short lengths after it is applied to the bond, of a feeding table having a plurality of parallel channels therein, a plurality of endless carrying members mounted in said channels, projections carried by said members extending above said table, the projections on the different members being opposite each other, a feeding shelf, and a collecting shelf, at opposite ends of said table, a driving mechanism, a ratchet wheel, an oscillating lever mounted to rotate about the axis thereof, a pawl carried thereby, a wheel driven from said driving mechanism, a connecting rod pivotally connected eccentrically of said driven wheel, and to said oscillating lever, means actuated by said ratchet wheel adapted respectively to actuate said members, and said presser mechanism, and means actuated by said driven wheel for actuating said shears, whereby said members will be moved unidirectionally and intermittently, and said shears will be operated when said members are stationary.
5. In a book binding machine, the combination of a flat-top for the machine, having a guide flange on one side thereof, a feeding mechanism whereby bonds are fed with one edge engaging said guide, a strip folder adapted to receive one edge of the bond, a presser roller alined with said folder and rotating upon an axis at right angles to the direction of movement of the bonds, means positively and intermittently driving said roller, means making said strip adhesive, shears whereby said strip is separated into short lengths after it is applied to the bond, a main driving mechanism, imparting a uni-directional intermittent movement to said feeding mechanism, and simultaneously actuating said driving means for said roller, and means actuating said shears when said feeding mechanism and said roller are at rest.
6. In a book-binding machine, the combination of a flat top for the machine, a feeding mechanism whereby bonds are fed along

5 said top, a strip folder, a presser roller alined with and disposed beyond said folder and rotating upon an axis at right angles to the direction of movement of the bonds, means
 10 positively and intermittently driving said roller, means adjacent to said feeding mechanism and to said folder whereby the bond is held against lateral movement while the strip is being laid and pressed thereon, means
 15 making said strip adhesive, shears whereby said strip is separated into short lengths after it is applied to the bond by said presser roller, a main driving mechanism, and means actuating said shears and said feeding mechanism intermittently, whereby an interval of rest is provided, during which the shears are actuated.

7. In a book binding machine, the combination of a flat top for the machine, a feeding mechanism whereby bonds are fed along said top, a strip folder, a presser roller alined with and beyond said folder and rotating upon an axis at right angles to the direction of movement of the bonds, a plurality of rollers opposite said folder, said presser roller and said other rollers being of the same diameter, means whereby said rollers are driven in the same direction at the same speed, means making said strip adhesive, shears whereby said strip is separated into short lengths after it is applied to the bond by said presser roller, and means respectively actuating said shears, and said feeding mechanism, and said rollers intermittently, whereby an interval of rest is provided during which said shears are actuated.

8. In a book binding machine, the combination of a flat top for the machine, a feeding mechanism whereby bonds are fed along said top, a strip folder, a power-driven presser-roller, alined with and beyond said folder and rotating upon an axis at right angles to the direction of feeding movement of the bonds, an idler roller mounted beneath said presser roller and in substantial engagement therewith, a plurality of power-driven rollers opposite said folder, idler rollers mounted in said top below said last mentioned rollers, respectively, and in engagement therewith, whereby a bond is held while the strip is being laid or pressed thereon, all of said power driven rollers being of the same diameter, means whereby all of said power driven rollers are rotated in the same direction at the same speed, means making said strip adhesive, shears whereby said strip is separated into short lengths after it is applied to the bond by said presser roller, a main driving mechanism, and means respectively actuating said shears and said feeding mechanism and said power driven rollers intermittently, whereby an interval of rest is provided during which the shears are actuated.

65 9. In a book binding machine, the combi-

nation with means making a strip adhesive, a folding mechanism whereby the strip is laid over the edge of a bond, a presser mechanism whereby the laid strip is applied to the bond, a block mounted on the frame, means whereby said block may be adjusted toward or from said folding mechanism, shears mounted on said block, whereby said strip is severed into short lengths after it is applied to the bond, an oscillatory shaft, adjustable means carried thereby for actuating the said shears, and means whereby said shaft may be rocked to actuate said shears, of a feeding table having a plurality of parallel channels therein, a plurality of continuous carrying members mounted in said channels, projections adjustably mounted on said members, extending above said table, the projections on the different members being opposite each other, a feeding shelf, and a collecting shelf at opposite ends of said table, a driving mechanism, and means respectively actuating said oscillating shaft and said presser mechanism intermittently.

10. In a book binding machine, the combination of a feeding mechanism for bonds, means making a strip adhesive, a folder mechanism, whereby the strip is laid over the edge of the bond, a presser mechanism whereby the laid strip is applied to the bond, shears whereby said strip is severed into short lengths, after it is applied to the bond, a main driving mechanism, a gear actuated thereby, a pawl and ratchet mechanism, a connecting rod actuating same, and eccentrically connected with said gear, means actuated by said pawl and ratchet mechanism for simultaneously actuating said feeding mechanism, and said presser mechanism, and means carried by said gear actuating said shears when said pawl and ratchet mechanism is inoperative.

11. In a book binding machine, the combination of a feeding mechanism for bonds, means making a strip adhesive, a folder comprising a back plate having oppositely disposed converging side flanges whereby a strip passing therethrough is folded and laid over the edge of a bond, a presser roller alined with and disposed beyond said folder, and rotating upon an axis at right angles to the direction of feeding movement of the bonds or pamphlets, whereby the laid strip is applied to the bond, shears whereby said strip is severed into short lengths after it is applied to the bond, a main driving mechanism and means actuating said shears, and said feeding and said presser mechanisms intermittently, whereby an interval of rest is provided during which the shears are actuated.

12. In a book binding machine, the combination of a feeding mechanism for bonds, means making a strip adhesive, a folder comprising a back plate having oppositely

disposed converging side flanges whereby the strip is folded and laid over the edge of the bond, a separating strip disposed midway between said side flanges, a presser 5 roller alined with and disposed beyond said folder and rotating upon an axis at right angles to the direction of the feeding movement of said bonds, whereby the laid strip is applied to the bond, shears whereby said 10 strip is severed into short lengths after it is applied to the bond, a main driving mechanism and means actuating said shears, and said feeding and said presser mechanisms intermittently, whereby an interval of rest is 15 provided during which the shears are actuated.

13. In a book binding machine, the combination of a feeding mechanism for bonds, means making a strip adhesive, a folder 20 comprising a back plate having oppositely disposed converging side flanges whereby the strip is folded and laid over the edge of a bond, a separating strip disposed midway between said side flanges, a spring clip carried by said separating strip whereby it may be detachably secured to one of said flanges, a presser roller alined with and disposed beyond said folder and rotating upon an axis at right angles to the direction of feeding 25 30 movement of the bonds, whereby the laid strip is applied to the bond, shears whereby said strip is severed into short lengths after it is applied to the bond, a main driving mechanism and means actuating said shears, and said feeding and said presser mechanisms intermittently, whereby an interval of rest is 35 provided during which the shears are actuated.

14. In a book binding machine, the combination of a feeding mechanism for bonds, a reel adapted to carry a roll of strip, a glue 40 pot, a frame carrying oppositely disposed rollers one of which has a peripheral rib

thereon and the other of which has a recess adapted to receive said rib disposed between 45 said glue pot and said reel, whereby said strip is creased or scored, a folder whereby the strip is laid over the edge of the bond, suitable strip guides between said glue pot and said folder, a presser roller alined with 50 and disposed beyond said folder and rotating upon an axis at right angles to the direction of feeding movement of the bonds, whereby the strip is fed and the laid portion thereof is applied to the bond, shears whereby said strip is severed into short lengths after it is applied to the bond, a main driving mechanism and means actuating said shears, and said feeding mechanism and said presser roller intermittently, whereby an interval of rest is provided during which the shears are actuated.

15. In a book binding machine, a feeding mechanism, whereby bonds are fed flat, a strip applying mechanism, means making a 60 strip adhesive, said bond feeding mechanism and said strip applying mechanism having a simultaneous unidirectional intermittent movement, a folder mechanism whereby the strip is laid over the edge of the bond, means 65 whereby the laid strip is permanently applied to the bond, shears whereby said strip is severed into short lengths after it is applied to the bond, a main driving mechanism, and means actuating said shears and 70 said feeding and said strip applying mechanisms whereby an interval of rest is provided during which said shears are actuated.

In witness whereof I have hereunto affixed my signature in the presence of two 80 witnesses.

DANIEL E. WOODHULL.
